UNITED STATES PATENT OFFICE.

JOHN LANE ALLEN, OF PRIDES CROSSING, MASSACHUSETTS.

DESIGN FOR A COMBINED CABINET AND ANTENNA FOR A RADIO RECEIVING SET.

Application filed February 19, 1926. Serial No. 16,597. Term of patent 14 years.

To all whom it may concern:

Be it known that I, JOHN L. ALLEN, a citizen of the United States, residing at Prides Crossing, in the county of Essex and State of Massachusetts, have invented a new, original, and ornamental Design for a Combined Cabinet and Antenna for a Radio Receiving Set, of which the following is a specification, reference being had to the ac-

companying drawing, forming part thereof.

The figure is a perspective view showing my new design.

I claim:

The ornamental design for a combined cabinet and antenna for a radio receiving set.

JOHN LANE ALLEN.
